UNITED STATES PATENT OFFICE.

THOMAS GRISWOLD, JR., OF MIDLAND, MICHIGAN, ASSIGNOR TO THE ONTARIO NICKEL COMPANY, LIMITED, OF WORTHINGTON, CANADA, A CORPORATION.

METHOD OF SEPARATING THE MORE SOLUBLE CONSTITUENTS OF A MATERIAL FROM THE LESS SOLUBLE CONSTITUENTS THEREOF.

No. 863,061.

Specification of Letters Patent.

Patented Aug. 13, 1907.

Original application filed January 17, 1906, Serial No. 296,552. Divided and this application filed January 12, 1907. Serial No. 351,939.

To all whom it may concern:

Be it known that I, THOMAS GRISWOLD, Jr., a citizen of the United States, and a resident of Midland, county of Midland, and State of Michigan, have invented a new and useful Improvement in Methods of Separating the More Soluble Constituents of a Material from the Less Soluble Constituents Thereof, of which the following is a specification, the principle of the invention being herein explained and the best mode in which I 10 have contemplated applying that principle so as to distinguish it from other inventions.

This, my present application, comprises subject matter divided out of my pending application, means for separating the more soluble constituents of a material 15 from the less soluble constituents thereof, filed January 17, 1906, Serial No. 296,552, and, together with such pending application, relates to the art of separating the more readily soluble constituents of materials from their less readily soluble or insoluble constituents by 20 the process of washing, and is particularly adapted to the treatment of flocculent precipitates, slimes, pulps, muds, sediments, and the like, the treatment of which constitutes an important feature of many industrial processes. It is also adapted to the washing of impurities and mother liquors out of crude products, the extraction of metals or the salts of metals from their ores, the extraction of sugars, extracts, colors, dyes, and the like. The object of such washing is usually to dissolve or take up, by means of a fluid solvent or wash, the soluble matter or "values" contained in the material being 25 treated, and to thereby separate these soluble "values" from the less soluble material or insoluble material, sediment, or sludge and from the insoluble matter that remains therein. By the term "values" is meant the substances to be recovered or, in some processes the impurities to be eliminated. These "values" may be capable of solution in a solvent, and, in that case, the separation would be based upon that solubility; or, the "values" may be capable of separation 30 from the other constituents of the material being treated by reason of their capacity to remain mechanically suspended for some time in a fluid medium, similarly to the separation of slimes in ordinary water gigs.

It will be seen from the further description of my invention that the capacity of any single constituent or several constituents to remain mechanically suspended for some time in a fluid medium is equivalent, insofar as the separation from the other constituents is concerned, to that constituent's entering into solution. 45 As an example of the washing process referred to, take a case in which it is desired to remove iron from an aqueous solution in which it exists as a soluble salt in conjunction with soluble salts of other metals incapable of precipitation by the reagent which is used to precipi-

tate the iron, such a salt being, for example, sodium chlorid. The iron may be precipitated by the addition of a proper proportion of an alkaline carbonate or hydrate, and, after agitation and settling, the flocculent iron precipitate will subside as a pulp or sludge and the clear solution of a part of the unprecipitated metals remain over it. This separation, although quite distinct, is a very slow one, is more dependent upon the area of the separating chamber than upon its depth, and the pulp cannot be settled to a concentrated form in any reasonable length of time, nor in any reasonable 55 amount of apparatus. The pulp, moreover, contains a low percentage of iron and also contains a correspondingly high percentage of water. The "values" remaining in solution in the pulp may be reduced by dilution with more water, agitation and resettling. Repeated washings, settlings and decantations will ultimately extract practically all the soluble "values" in the pulp, but in very much diluted solution, and at the expense of much solvent, although weak wash water may be systematically increased in strength, as ordinarily practiced, by being used with pulps of a progressively increasing percentage of "values."

The treatment of large quantities of materials by the above method requires the use of many large chambers provided with stirring devices and power to drive them, 60 and the tying up of a large money investment in material in process, and, consequently, this progressive treatment cannot be utilized to the fullest extent because of a commercially prohibitive complication of apparatus and supervision.

Some pulps are easily treated by filtration, leaching, settlement and decantation, or other processes. Some are of a colloidal nature and filtration will not readily remove the colloids. Others will clog a filter so soon that filtration is impracticable.

My invention is especially adapted to treat rapidly and efficiently those slimes or pulps which, having a slow rate of settling, make separation by settlement and decantation, as ordinarily practiced, very slow, and which are not adapted to economical treatment 95 by filtration or leaching.

The invention aims to accomplish the separations above outlined, or, by suitable adaptation, to accomplish such separations as are required in other industries, as, for instance, the recovery of cyanid of gold 100 from slimes.

The object of my present invention is to wash the pulp and to then remove and wash the resulting sludge, these washing and separating operations being automatically repeated any desired number of times; and, 105 further, to accomplish these results in a rapid, economical and efficient manner.

Further objects are to reduce the investment in ap-

paratus and machinery, to remove the "values" in pulps, slimes, etc., to as full an extent as may be desired, to reduce to a low sum the investment tied up in the material in process, and to extract the soluble matter in as concentrated a form as possible, thereby reducing the quantity of solvent or wash-water required, and the tankage necessary to hold the extracted "values". This latter improvement, viz. that of extracting the "values" in as concentrated a form as possible and thereby reducing the tankage, will be found to be a very important part of my invention.

In this invention, in effect, a solvent or washing fluid is caused to traverse in one direction through a series of dissolving or washing operations, and pulp or sludge is simultaneously caused to traverse in the opposite direction through the same series. The sludge is thereby repeatedly washed, settled and rewashed in solvent of progressively increasing solvent power and carrying a decreasing burden of "values" until, when discharged at the end of such series of steps the sludge is practically deprived of soluble "values." The arrangement is such that the solvent entering the series fresh is used to wash sludge that has been deprived of nearly all its soluble "values". Such partly charged solvent is thereafter used in the subsequent steps of the series to successively wash the charges of sludge, each of which charges is somewhat stronger in soluble "values" than the previous one. The effect on the fresh solvent is to successively add to it quantities of soluble "values" until, when the solvent leaves the series, it is highly charged with these "values."

The annexed drawings and the following description set forth in detail one mode of carrying out the invention, such disclosed mode, however, constituting but one of various ways in which the principle of the invention may be used.

In said annexed drawings: Figure 1 is a vertical longitudinal section of an approved form of apparatus adapted to the carrying out of my method. Fig. 2 is a top plan view of the same. Fig. 3 is a vertical transverse section taken on the line 3-3 of Figs. 1 and 2. Fig. 4 is a side elevation of the apparatus for dipping the fluid or semi-fluid sludge from one chamber-compartment to another, the dipping vessel being shown in its lifting position. Fig. 5 is a similar view, showing the vessel in its discharging position. Fig. 6 is a top plan view of the parts illustrated in Fig. 4. Fig. 7 is a perspective of a part of the washing apparatus in which, for the sake of clearness, the stirring devices are omitted. This figure shows the means of operating the dippers.

The apparatus shown in the aforesaid figures consists in a series of settling chambers, the consecutive members of the series being connected together by pipes or conduits, there being interposed in the length of each conduit a suitable mixing apparatus for mixing the sediment or sludge taken from the bottom of one settling chamber with the solvent solution drawn from the top of that settling chamber which is two removed from the one from which the sediment was taken. It needs scarcely be stated that the particular form of mixing chambers is immaterial. Thus, while they are shown built separately and connected by pipes to the separating chambers, they might just as well be built as an integral part of the settling chambers, in which

case the pipes or conduits could be replaced by openings in the partition walls.

In general, the method of operation is as follows: The pulp or other material to be treated is admitted to the first mixing chamber of the series where solvent that contains a large percent of soluble "values" is added to it. The mixture of pulp and solvent thus formed is settled in the first settling chamber of the series, the effect of settling being to separate the mixture into a sludge weaker in soluble "values" than the original pulp, and a solvent more heavily charged with soluble values than before. The heavily charged solvent is discharged from the apparatus and then the sludge that remains is passed to the next mixing chamber, where it is again mixed with solvent weaker in soluble "values" than the solvent employed in the first mixing chamber. The resultant mixture is again settled in the next settling chamber of the series and is by so settling once more separated into a still weaker sludge and a more heavily charged solvent. The process continues through the whole series of receptacles until the resultant sludge deprived of practically all of its soluble "values" is discharged at the end of the series.

In the drawings F is a vessel containing the settling chambers 1, 2, 3, 4, which are preferably hopper-bottomed. While I have thus shown and described the whole series of settling chambers as being built in one tank structure F, I do not desire to confine myself to such construction, it being obvious that the various settling chambers might be separated if desired.

In each receptacle I prefer to provide inclined baffle plates *a* which extend across the tank F from side to side. The purpose of these baffle plates is to increase the area of surface upon which the sludge may settle, to reduce the vertical distance through which any given particle of suspended sludge must fall before meeting a contacting surface, thereby increasing the working capacity of the separating chambers over the capacity they would have were the baffle plates omitted.

A, B, C, D, and E are termed "mixing chambers," their office being to mix the sludge or sediment from one settling chamber with solvent from the settling chamber two removed therefrom. These mixing chambers are small tanks divided into three compartments B¹, B² and B³, as shown in Fig. 3. The first compartment B¹ receives the sludge from the bottom of the separating chamber 1, the sludge passing through the pipe p¹. The sludge is dipped by means of a mechanical dipper which will be later described, from compartment B¹ into compartment B², where it mixes with washing or solvent fluid that enters through the pipe K³ being drawn from a point near or at the surface of the liquid in settling chamber 3. The sludge and solvent pass down to the bottom of compartment B² and thence through an opening O into compartment B³ in which is mounted a revolving shaft S carrying stirring paddles P. This stirring apparatus thoroughly mixes the sludge and solvent, the mixture being delivered through pipe m² into the top of settling chamber 2, where the mixture is settled.

Beginning at the left in Fig. 2, fresh wash-water, solvent, or other suitable medium for dissolving or taking up the "values", enters the system at *e*, flows by gravity through the mixing apparatus D and the pipe m¹ through successive alternate mixing and settling

chambers, as shown by arrows, and runs out at *f* charged with the soluble "values" which it has taken up from the pulp and sludge during its passage through the apparatus. Untreated pulp is run into the apparatus at *g*, and delivered by means of the dipping mechanism into the middle compartment *A*² of the washer *A*. Here the pulp mixes with the strongly charged solution which runs into *A*² from the separating chamber 2 through pipe *K*². The mixture flows 10 down and into the agitating compartment *A*³ where the pulp and solvent are thoroughly mixed and the pulp is washed. From *A*³ the thin mixture flows through the pipe *m*' into the settling chamber 1, and thence down diagonally as shown by the arrow in Fig. 15 1, and up through the spaces between the baffles *a*. Here the sludge drops out and slides down the baffle plates into the hopper below. The concentrated solution leaves the sludge on the baffle plates and flows out at *f*. The sludge which has been separated and 20 settled in receptacle 1 passes by pipe *p*¹ into compartment *B*¹ of the mixing chamber *B*. Through the pipe *K*² a less concentrated solution simultaneously passes from settling chamber 3 into compartment *B*² of mixing chamber *B* of the mixing apparatus. Thorough 25 mixture takes place in *B*³, and the resulting fluid is delivered to receptacle 2 where it settles in the same manner as has been described for receptacle 1. In similar manner settled sludge from 2 is washed in *C*, resettled in 3, and rewatched in *D* with fresh solvent, 30 resettled in 4 and dipped out of the system by the dipper *E*.

It is thus seen that sludge from the first settling chamber is repeatedly washed in solvent carrying a constantly decreasing burden of "values", until when discharged from *E* through pipe *h* the sludge is practically free from soluble "values". The fresh solvent let in at *e* is repeatedly used to wash sludge in which the soluble "values" are constantly increasing until when the solvent is let out at *f* it is highly charged with these "values". This invention, then, consists in effecting a contrary flow of sludge and solvent through a series of mixing and settling chambers and the consequent production of a solution concentrated in "values". By increasing the number of mixing and separating units in the series, the percentage of soluble "values" remaining in the discharged sludge may be reduced indefinitely and the efficiency of extraction may be raised to a correspondingly high point.

It will be understood from the foregoing description 50 that the successful operation of this apparatus does not depend to any great extent upon the particular form of mechanism by which the sludge is caused to flow from one compartment of the vessel *F* through the mixer into another compartment during the process of mixing. Any suitable form of device may be used for this purpose without departing from the spirit of my invention, but for the purpose of illustration I have shown a form of dipping apparatus which operates satisfactorily on flocculent precipitates. This dipping apparatus 55 consists in a suitable receptacle or measuring tank *N* pivotally mounted at its lower end to an upright support *N*' capable of vertical movement, so that the tank can be dipped into and out of the sludge in the first compartment of the mixing apparatus.

60 To empty the tank when it is raised to the top of its

travel I provide a suitable trip *n* preferably comprising a horizontal projection at the lower end of the tank which contacts with the under side of a suitable fixed stop *n*' carried by any convenient part of the framework, so as to overbalance the pivotally mounted tank 70 when it reaches the top of its travel.

To permit the tank to retain its vertical position after the liquid has been emptied from it and the support *N*' has assumed its lowermost position, I provide a suitable counterbalance *n*² projecting from the side of the tank 75 opposite that on which the trip is located. The vertical movement of the tank and the upright support on which it is mounted may be accomplished by any suitable and convenient means, one form of which is shown in Fig. 7.

To insure that the measuring tank shall always contain the exact amount of sludge so as to produce uniform flow of sludge, an opening or perforation may be provided at any desired height at the side of the tank 80 so that the tank cannot fill above that point.

I prefer in practice to secure a uniform flow of sludge through the entire apparatus by operating all the various dippers *N* simultaneously or in rotation, the former being accomplished by the means illustrated in Fig. 7, where three mixing chambers are shown connected to the corresponding settling chambers. The dippers are hung on bell-cranks *n*³ which are operated by a reciprocating pulling bar *N*² to which they are pivotally connected. A to-and-fro motion of the bar causes an up-and-down motion of the dippers. Some 90 materials, such as sands, finely crushed or ground ores, and the like, will require special forms of dippers and settlers.

With many materials the baffles aid in producing rapid settlement and separation. Various forms of 100 baffles may be used as desired. It should also be pointed out that it is not essential to their proper action that the mixture of solvent and sludge be fed into the settling tanks beneath such baffles, as is shown in the preferred form of apparatus illustrated, for said mixture may obviously be delivered, if found desirable, onto their tops just as well.

While I have shown and described the apparatus 105 organized to secure the necessary flow of solvent and sludge by dipping the sludge and permitting the solvent to flow by gravity through the receptacles, it is evident that the same purpose might be attained by dipping or pumping both the solvent and sludge, or pumping the solvent and permitting the sludge to flow by gravity.

I wish to call particular attention to the fact that in the claims following this description my choice of names for the two constituents of the material which are separated one from the other, involves the use of "the more soluble constituents" and "the less soluble constituents", and the choice of these names is made advisedly, for the reason that materials which are commonly classed as "insoluble" are regarded by chemists as "soluble", and are differentiated into classes which are "slightly soluble" and "very slightly soluble". 120 This invention is adapted to the separation of the "more soluble" constituents of a material from its "less soluble" constituents. As regards the separation which takes place in each successive step of the operation, the fact should be noted that neither the fluid nor the so¹ 125

constituents are completely separated. At least, it is not necessary to the successful operation of the invention that they should be so separated. It is necessary only that the mixture be separated to such an extent 5 that the lower or heavier portion contains a larger percentage of the undissolved or less soluble constituents than does the upper or lighter portion; or, in some cases, that the lower portion contains all the undissolved or less soluble constituents and a portion of the 10 more soluble constituents either undissolved or in solution. In case the less soluble constituents be lighter than the solvent or washing fluid the undissolved constituents will predominate in the upper portion and the more soluble dissolved constituents will predominate 15 in the lower portion. This would be the case, if, for instance, the material being treated were an oil lighter than the water used as a wash to remove traces of acid or other constituents soluble in water or capable of removal by it. The use of the term "separated" is 20 meant to cover all these cases, the eventual result being governed, first, by the kind of material being treated; secondly, by the number of settling and mixing chambers utilized; and, thirdly, by various changes and modifications which may creep in at times as separate elements to modify the general result, such general result being, as outlined above, the separation of the 25 more soluble constituents of a material from the less soluble constituents thereof.

Other modes of applying the principle of my invention 30 may be employed instead of the one explained, change being made as regards the process herein disclosed, provided the step or steps stated by any one of the following claims or the equivalents of such stated step or steps be employed.

35 I therefore particularly point out and distinctly claim as my invention:—

1. The method of separating the more soluble constituents of a material from the less soluble constituents thereof, which consists in simultaneously passing a fluid 40 solvent and the material in general opposite directions through a series of mixing and settling chambers, said solvent and material flowing in a joint current through said mixing chambers and in counter currents through said settling chambers.

45 2. The method of separating the more soluble constituents of a material from the less soluble constituents thereof, which consists in simultaneously passing a fluid solvent and the material in general opposite directions through a series of alternate mixing and settling chambers, 50 said solvent and material flowing in a joint current through said mixing chambers and in counter currents through said settling chamber.

55 3. The method of separating the more soluble constituents of a material from the less soluble constituents thereof, which consists in simultaneously passing a fluid solvent in one general direction through a series of mixing and settling chambers and simultaneously passing the material continuously in the opposite general direction through said chambers, said solvent and material flowing 60 in a joint current through said mixing chambers and in counter currents through said settling chambers.

65 4. The method of separating the more soluble constituents of a material from the less soluble constituents thereof, which consists in simultaneously passing a fluid solvent in one general direction through a series of alternate mixing and settling chambers and simultaneously passing the material continuously in the opposite general direction through said chambers, said solvent and material flowing 70 in a joint current through said mixing chambers and in counter currents through said settling chambers.

75 5. In a method of separating the more soluble constituents of a material from the less soluble constituents

thereof, the steps which consist in agitating such material with a solvent; settling out the undissolved material; and, then repeating the cycle, successive mixtures being separated in successive settling chambers of a series, the solvent being simultaneously caused to flow in the same direction as said material in the successive agitating steps and in the opposite direction thereto in the settling steps. 75

80 6. In a method of separating the more soluble constituents of a material from the less soluble constituents thereof, the steps which consist, in pumping the material; agitating the same; settling it; and, then repeating the cycle, said material being settled in successive chambers of a series, the solvent being continuously and simultaneously caused to flow in the same direction as said material in the successive agitating steps and allowed to flow by gravity in the opposite direction thereto in the settling steps. 85

90 7. In a method of separating the more soluble constituents of a material from the less soluble constituents thereof, the steps which consist, in pumping the material in one of a series of chambers; agitating the same in a second chamber; settling it in a third chamber; and, then, repeating the cycle, the second agitation and settling being 9 accomplished in other chambers of said series, the solvent being simultaneously passed through said agitating chambers in the same direction and in said settling chambers in the opposite direction as said material. 95

100 8. In a method of separating the more soluble constituents of a material from the less soluble constituents thereof, the steps which consist, in pumping the material in one of a series of chambers; agitating the same in one of a second series of chambers; settling it in another chamber of said first series; and, then, repeating the cycle, 105 said material being settled in successive chambers of said first series, the solvent being simultaneously caused to flow through said agitating chambers in the same direction as said material and allowed to flow by gravity in the opposite direction in said settling chambers. 110

115 9. In a method of separating the more soluble constituents of a material from the less soluble constituents thereof, the steps which consist in alternately mixing together and settling a fluid solvent and the material, said solvent and material being caused to flow in a joint current in successive mixing steps and in counter currents in successive settling steps. 115

120 10. In a method of separating the more soluble constituents of a material from the less soluble constituents thereof, the steps which consist in causing a fluid solvent to traverse a series of alternate mixing and settling chambers and simultaneously causing the material to traverse said chambers in a counter direction, whereby the two currents are alternately joined in said mixing chambers and separated by settling in said settling chambers so 125 that a fluid solvent whose percentage of dissolved values is increasing encounters material whose successive portions contain increasing percentages of soluble constituents. 125

130 11. In a method of separating the more soluble constituents of a material from the less soluble constituents thereof, the steps which consist in alternately mixing together and settling a fluid solvent and the solid material, said solvent and material being caused to flow in a joint current in said mixing steps and in counter currents in 135 said settling steps. 130

140 12. In a method of separating the more soluble constituents of a material from the less soluble constituents thereof, the steps which consist in causing a fluid solvent to traverse a series of alternate mixing and settling devices and simultaneously causing the material to traverse said mixing devices in a joint current and said settling chambers in counter currents, whereby the two currents are alternately mixed together and separated so that a fluid solvent whose percentage of dissolved values is increasing 145 encounters material whose successive portions contain increasing percentages of soluble constituents. 145

150 13. The method of separating the more soluble constituents of a material from the less soluble constituents thereof, which consists in independently mixing two quantities of such material with a solvent, settling such two mixtures, mixing two of the unlike constituents thus separated, and re-settling such last mixture. 150

14. The method of separating the more soluble constituents of a material from the less soluble constituents thereof, which consists in independently mixing two quantities of such material retaining different proportions of soluble values with two quantities of solvent unequally charged with such values, settling such two mixtures, mixing two of the unlike constituents thus separated, and re-settling such last mixture. 5
15. The method of separating the more soluble constituents of a material from the less soluble constituents thereof, which consists in independently mixing two quantities of such material retaining different proportions of soluble values with two quantities of solvent correspondingly unequally charged with such values, settling such two mixtures, mixing two of the unlike constituents thus separated, and re-settling such last mixture. 10
16. The method of separating the more soluble constituents of a material from the less soluble constituents thereof, which consists in mixing a quantity of such material with a quantity of solvent, independently mixing a second quantity of material with a second quantity of solvent both containing a smaller proportion of soluble values than said first quantities, settling such two mixtures, mixing the material remaining from such first mixture with the clarified solvent from such second mixture, and re-settling such last mixture. 15
17. The method of separating the more soluble constituents of a material from the less soluble constituents thereof, which consists in continuously settling in two separate chambers currents of the material mixed with a solvent, drawing off from said chambers currents of undissolved material and clarified solvent, mixing currents of unlike constituents from said two chambers, and continuously settling such last mixture in a third chamber. 20
18. The method of separating the more soluble constituents of a material from the less soluble constituents thereof, which consists in continuously settling in two separate chambers currents made up of quantities of such material retaining different proportions of values mixed with quantities of solvent charged with different proportions of such values, drawing off from said chambers currents of undissolved material and clarified solvent, mixing currents of unlike constituents from said two chambers, and continuously settling such mixture in a third chamber. 25
19. The method of separating the more soluble constituents of a material from the less soluble constituents thereof, which consists in continuously settling in two separate chambers currents made up of quantities of such material, respectively retaining a greater and less proportion of values, mixed with quantities of solvent relatively similarly charged with such values, drawing off from said chambers currents of undissolved material and clarified solvent, mixing currents of unlike constituents from said two chambers, and continuously settling such mixture in a third chamber. 30
20. The method of separating the more soluble constituents of a material from the less soluble constituents thereof, which consists in continuously settling in one chamber a current made up of a quantity of such material mixed with a quantity of solvent, similarly settling in another chamber another current made up of a quantity of material mixed with a quantity of solvent, both of said second quantities containing a smaller proportion of soluble values than said first quantities, drawing off from said two chambers currents of undissolved material and clarified solvent, mixing the current of material from said first chamber with the clarified solvent from said second chamber, and continuously settling such last mixture in a third chamber. 35
21. The method of separating the more soluble constituents of a material from the less soluble constituents thereof, which consists in continuously mixing, at consecutive stations in its course, a current of such material with a current of solvent, flowing in a general opposite direction, and thereupon settling the resultant mixtures, the undissolved material remaining from any one station being mixed with the clarified solvent from a station twice removed therefrom. 40
22. The method of separating the more soluble constituents of a material from the less soluble constituents thereof, which consists in causing currents of the material and a solvent to flow through a series of connected chambers in counter-directions wherein the said material and solvent are alternately mixed together and separated by settling in such manner that the constituents of a mixture separated in any one chamber shall have been previously separated respectively in the two chambers situated serially on either side of such first-named chamber. 45
23. The method of separating the more soluble constituents of a material from the less soluble constituents thereof, which consists in causing currents of the material and a solvent to flow through a series of connected chambers in counter-directions wherein the said material and solvent are alternately mixed together and separated by settling in such manner that the constituents of a mixture separated in any one chamber shall have been previously separated as unlike constituents respectively in the two chambers situated serially on either side of said first-named chamber. 50
24. The method of separating the more soluble constituents of a material from the less soluble constituents thereof, which consists in continuously separating mixtures of the material and a solvent in a series of settling chambers in such manner that the mixture separated in any chamber except the first and last in the series consists of the material and solvent previously separated respectively in the two settling chambers located serially on either side of said first-named chamber. 55
25. The method of separating the more soluble constituents of a material from the less soluble constituents thereof, which consists in continuously mixing the material and a solvent in a series of mixing chambers and separating the mixtures in settling chambers directly related serially thereto in such manner that the two constituents mixed in any mixing chamber except the first and last of the series shall have been separated previously as unlike constituents respectively in settling chambers directly related respectively to mixing chambers situated serially on either side of the said mixing chambers. 60
26. The method of separating the more soluble constituents of a material from the less soluble constituents thereof, which consists in continuously feeding the material and a fluid solvent into opposite ends of a series of mixing chambers, each mixing chamber being directly related to one of a second series of settling chambers; continuously mixing currents of the material and solvent in the mixing chambers and separating the resulting mixture in the respectively related settling chambers in such manner that the material and solvent separated in a settling chamber shall have been previously separated as unlike constituents in the two settling chambers located serially on either side of the said chamber. 65
27. The method of separating the more soluble constituents of a material from the less soluble constituents thereof, which consists in passing a continuous current of the material into the first one of a series of compound chambers, and a continuous current of a solvent into the last one of the same series, each compound chamber consisting of a mixing chamber connected with a settling chamber; mixing and separating untreated material with nearly spent solvent in the first compound chamber, mixing and separating nearly treated material and fresh solvent in the last compound chamber; mixing and reseparating in any other compound chamber the unlike portions of material and solvent respectively which have been separated just previously in the compound chambers located serially on either side of the said compound chamber; drawing off continuously from the last of the series treated material; and from the first of the series spent solvent. 70
